KNITTING MACHINE

Sidney Arthur Welch, Albert Fairholme Guyler,
William Henry Boaler, and John Thomas
Ashby, Spondon, near Derby, England, assign-
ors to Celanese Corporation of America, a cor-
poration of Delaware

Application December 12, 1931, Serial No. 580,597
In Great Britain January 26, 1931

16 Claims. (Cl. 66—110)

This invention relates to knitting machines, and particularly to flat weft knitting machines of the kind which are provided with sliding needles and sinkers operated by suitable cams.

5 The invention is principally concerned with the operation of the sinkers, not only in machines having a constant stroke, but also those having a variable stroke, for example, the machines described in U. S. application S. No. 469,448 filed 21st July, 1930 in which the stroke is varied in accordance with the width at any course of the fabric or article being knitted, and the frequency of the courses is made substantially inversely proportional to the lengths of the courses.

10 15 The invention is also concerned with means for changing the presser cam lead in machines of the above character employing bearded needles.

According to the invention, the sinker operating cams are so arranged as to occupy alternately at successive courses two positions which are situated on each side of, and preferably substantially symmetrical with respect to, the knitting position determined by the needle cams, each position being such a distance to the side of the needle cams as to afford the requisite lead in either direction of movement of the needle and sinker cams. Conveniently two cams are employed, slideable in the direction of the traverse to give the correct lead in successive strokes, and movable towards and away from the needles out of and into loop-forming position. These cams may each serve alternately as loop-forming and holding-down cams, their movements towards and away from the needles causing them to exchange functions at the time when the lead is adjusted, i. e., at the end of each stroke. With such dual-purpose cams, it is only necessary to provide each with a profile suitable for either operation.

40 In the case of machines operating with a traverse of constant length, the sinker operating means may be caused to change the sinker lead by means of fixed (though preferably adjustable) stops mounted on the machine frame and engaged by mechanism on the cam box connected to the sinker operating means. Similar stops may be used in the case of variable traverse mechanism, as for example that described in U. S. application S. No. 469,448, but it is preferred to effect the sinker lead change from the mechanism employed to reverse the direction of motion of the cam box itself, so that the lead change always takes place at the correct instant whatever the length of stroke of the cam box.

45 50 55 The sinkers may be used with latch needles, though they are more usually associated with bearded needles, particularly in the manufacture of fine gauge knit-wear. With bearded needles, provision has to be made for pressing the beards on the descent of the needles, and here again there must be a change of lead at successive

courses. For this purpose, a single cam may be employed, movable from one position to another at the end of each stroke, or, and more conveniently, two cams may be used movable alternately into and out of working position. The presser cam 5 or cams may be operated directly or indirectly by the mechanism employed to effect the sinker lead change, or by entirely independent mechanism. It is preferred for this purpose to employ individual presser jacks, acting on the individual needles and acted upon in turn by the presser cams.

10 15 The arrangements above described may conveniently be used in connection with the yarn guide control mechanism described in U. S. application S. No. 580,596 filed Dec. 12, 1931 for operating the yarn guide in correct relationship to the needle cams and sinker cams.

20 25 The invention will now be described in greater detail with reference to the accompanying drawings which illustrate the invention as applied to a knitting machine of the kind described in U. S. application S. No. 469,448, and in connection with the yarn guide driving mechanism described in U. S. application S. No. 580,596 filed Dec. 12, 1931. It is to be understood, however, 25 that this description is given by way of example only, and is in no respect limitative.

30 35 Fig. 1 is a rear elevation of the mechanism according to the invention as applied to a knitting machine of the kind described in U. S. application S. No. 469,448;

Fig. 2 is a plan view of Fig. 1 and Fig. 3 a side elevation in section through the line 3—3 of Fig. 1;

Fig. 4 shows a modification of the yarn guide 35 driving mechanism illustrated in Fig. 1;

Figs. 5 and 6 show details on a somewhat large scale of the mechanism shown in Figs. 2 and 3 respectively; and

40 Figs. 7 and 8 show diagrammatically the relative positions of the sinker cams, presser cams and needle cams for two directions of travel.

45 Referring to Figs. 1, 2 and 3, a series of needles 11 shown clearly in Fig. 3, are mounted in a needle bed 12 and are operated by means of cams 45 13 carried in a cam box 14 sliding upon a horizontal bar 15. The cam box 14 is driven by means of a mechanism comprising a cam box carriage 17 which is provided with a disc 18, of which a segment 19 is cut away (at the top of 50 the disc as shown), the disc 18 being mounted upon a horizontal bar 20. The carriage 17 also carries four pulleys 21 mounted upon shafts 22 symmetrically disposed around the disc 18. The belt 23 runs freely between the pulleys 21 and 55 55 the cut away portion 19 of the disc 18, but on the other side of the disc (as illustrated the lower side), the belt 23 is nipped between the disc 18 and pulleys 21. The belt 23 runs round a pair of pulleys 24, of which one is shown to 60

the right of Figs. 1 and 2, and is driven by mechanism (not shown) lying to the left of these figures. The disc 18 is prevented from rotating by means of a crank 25 rigidly fixed to it, whose 5 free end bears upon two horizontal bars 26, 27 adjustably mounted upon a bar 28. For this reason, the motion of the belt 23 drives the carriage 17 and the disc 18, the cam box 14 being driven from the disc 18 by means of a pin 29 10 fixed into a block 30 situated in a slot 31 in the rear face of the cam box. When the cam box reaches the end of its traverse, the crank member 25 slips over the end of the bars 26 and 27 allowing the disc 18 to rotate for half a revolution, which brings the cut away portion 19 of 15 the disc 18 opposite the other run of the belt 23, and the block 30 and pin 29 to the other end of the slot 31. In this manner the carriage 17 is clamped to the other run of the belt, and is driven 20 in the opposite direction, the process being repeated in reverse at the other end of the traverse. The sinkers 34 are operated by means of cams 35, 36 which are driven from the knitting cam box 14. The sinker cams 35, 36 proceed in lead 25 of the knitting cams 13, the lead being reversed at the end of the knitting traverse in the following manner.

Referring particularly to the detailed Figs. 5 and 6, the cams 35, 36 are mounted upon a plate 38 which in turn is slidably mounted on the under-side of the plate 39 fixed rigidly to the cam box 14. The plate 38 has an extension 40 provided at one end with two projections 41, 42 between which lies the upper end 43 of a sickle shaped lever 44. The lever 44 is pivoted at 45 to the rear face of the cam box 14, and is provided with a heel 46 near the pivot point, and a toe 47 at the lower end. The heel 46 and the toe 47 engage alternately with the block 30 through which the cam box 14 is driven, according to whether the block is at the upper or lower end of the slot 31, that is according to whether the knitting cams are moving to the left or to the right. In this manner the end 43 engaging one or other of the projections 41, 42 slides the plate 38 and the cams 35, 36 to the left or right, and the cams 35, 36 are always caused to be in lead of the knitting cams 13. At the same time the cams 35 and 36 exchange functions, thereby increasing the amount of change of lead effectively made. Thus the leading cam performs the function of forming loops round the needles prior to knitting, while the second cam is a holding-down cam and projects more than the leading cam. For this purpose one cam slides forward and the other back and this effect is produced by causing pegs 50, 51 to extend from the cams 35 and 36 through oblique slots 52, 53 in the top plate 39. The cams 35, 36 are mounted under the plate 38 in such a manner as to be able to slide slightly forward and back, so that when the knitting cams are moving to the right, the pegs 50, 51 occupy the right-hand ends of the slots 52, 53, the leading cam 36 being thereby drawn back slightly on the following cam 35 being pushed forward. When the knitting cams 13 are moving to the left, the cam 35 is drawn back, while the cam 36 is pushed forward. Thus, in addition to moving slightly in the direction in which the lead is required, the two cams 35, 36 exchange functions.

It will be understood that the cams 35, 36 have their operating surfaces projecting from their lower faces so as to engage the upstanding butts 37 of the sinkers lying below the plate 38, as shown in Fig. 3. The operating surfaces work in conjunc-

tion with other operating surfaces projecting from the lower face of the plate 38 to form a cam groove which provides for both the inward and outward movements of the sinkers.

In a similar manner the presser cam, of which 5 two are provided at 55, 56 is caused to operate in lead of the knitting cams. The two cams 55, 56 are mounted together in one piece upon a bracket 57 fixed to the top of the plate 39 and which are operated by means of a plate 58 fixed 10 to the sliding plate 38. In this manner when the knitting cams are moving to the right, the right-hand presser cam 56 is pushed forward by engagement of its rear edge with the right-hand corner of the plate 58, the left-hand presser cam 15 55 being swung back to an inoperative position. When the knitting cams move to the left, the plate 58 is moved to the left with the plate 38 and relatively to the plate 39 carrying the presser cams 55, 56. This causes the rear edge of the 20 cam 55 to be engaged by the plate 58, so that the cam 55 swings forward and the cam 56 swings back to the inoperative position. The cams 55 and 56 act upon presser jacks 59, shown in Fig. 6.

The relative positions of the actual sinker cams, 25 presser cams and needle cams are shown dia- 30 grammatically in Figs. 7 and 8. In Fig. 7 the needle cams 90, 91 are shown swung through an angle of 90° so as to lie in the same plane as the sinker cams. Referring to the sinker cams them- 35 selves the cam blocks 92, 93 and the counter cam 94 are mounted rigidly on the underside of the plate 38 referred to above, while the cam blocks 95, 96 are mounted upon the plates 35, 36 which are adapted to slide to and fro in slots 97 in the 35 plate 38. This motion is effected as described above by the pins 50, 51 sliding in the slots 52, 53.

As shown in solid lines in Fig. 7 the needle cams, sinker cams and presser cams are moving to the left, and it will be seen that the centre 40 line of the sinker cams 95, 96 is to the left of the centre line of the needle cams while of the two presser cams 55, 56 the left hand cam 55 is pressed into operating position. Further, it will be noted that the leading sinker cam 95 is drawn back to 45 cause the sinkers to form loops round the needles prior to knitting, while the following cam 96 is pushed forward as indicated by the solid arrows to act as a holding down cam during the knitting operation of the needles. When, however, 50 the needle cams move to the right the plate 38 slips to the right so bringing the centre line sinker cams 92—96 to the other side of the centre line of the needle cams 90, 91 as shown in dotted lines. Further, as shown by the dotted arrows the cam 55 55 is pressed into a forward position while cam 96 is drawn back. In addition the right hand sinker cam 56 is pressed forward into operating position by the plate 58, while the left hand sinker cam 55 is drawn back to an inoperative position. 60

In co-operation with the sinker cam lead change and presser cam lead change mechanism described above, means may conveniently be provided for reversing the lead of the yarn guide, as described and claimed in U. S. application S. No. 580,596. 65 Yarn is supplied from yarn guides 60 sliding upon bars 61, and operated by fingers 62 sliding upon bars 63. While in this description the members 60 and 62 are described as sliding on the bars 61, 63, an arrangement convenient for a single ma- 70chine, they may be fixed rigidly to the bars, which are then caused to slide bodily in their bearings in the end frames 66 of the machine. This arrangement is convenient where a series of machines producing a number of articles simultane- 75

ously are driven by common means, the bars extending past all the machines, and carrying a set of guides and fingers for each machine. Similar conditions apply to the bar 15 on which the knitting cams have been described as sliding.

The fingers 62 are driven by a yarn guide carriage 64 mounted upon a bar 65 and pushed from end to end of the machine in lead of the knitting cam, so that yarn is fed to the needles before the knitting cams operate upon them. For this purpose two cams 67, 68 are carried by an enlargement 69 of the upper shafts 22 on the knitting cam carriage 17. The cams 67, 68 are respectively engaged by two levers 70, 71 pivoted to the yarn guide carriage 64 and each cam is provided with a V-shaped notch 72, 73 which are engaged by bowls 75, 76 at the lower ends of the levers 70, 71. When the knitting cams are moving to the right (as shown), the bowl 75 on the right-hand lever 20 70 is engaged in the notch 72 of its own cam 67, while the bowl 76 on the other lever 71 rides upon the horizontal upper surface of its cam 68. At the end of the traverse, the bowl 75 attached to the lower end of the lever 70 engages 25 with a stop 77 carried by the horizontal bar 27, and is thereby prevented from moving further to the right. The bowl 75 is, therefore, compelled to ride up the V-shaped notch to the top of the cam 67 while the cams 67, 68 move on beneath 30 it with the knitting cams 13 until the bowl 76 on the other lever 71 drops into the notch 73 of the other cam 68. The knitting cams 13 now come to rest at the end of the traverse, and move in the reverse direction, that is to the left, the bowl 35 76 on the lever 71 being in engagement in the notch 73 of the cam 68, ready to drive the yarn guides to the left in lead of the knitting cams 13 as desired.

In order to adjust the amount of lead imparted to the yarn guide the cams 67, 68 are slidably adjustable on their support 69, in order that the respective positions of the two notches 72, 73 may be adjusted. Slots 79 are provided in the cams to allow of such adjustment. Alternatively, 45 however, adjustment may be made by moving the pivot points 80, 81 of the two levers 70, 71, and means for this purpose are illustrated in Fig. 4, wherein slots 82, 83 are provided in which the pivot points 80, 81 may be adjusted. In this case, 50 since adjustment of the cams is unnecessary, the two cams can be made in one piece as illustrated at 85 in Fig. 4. In this figure, instead of providing V-shaped notches, ramps 86, 87 are provided for the bowls 75, 76 to ride up at the end 55 of the traverse.

What we claim and desire to secure by Letters Patent is:—

1. A flat knitting machine comprising a series 60 of sliding needles, knitting cams adapted to traverse in either direction along said needle series, a series of sinkers, two similar sinker cams adapted to traverse in either direction along said needle series, and means to move said cams alternately from loop sinking position to holding-down position and vice versa at the end of each traverse, in accordance with the alternate movements of the knitting cams in opposite directions, so as to maintain the leading sinker cam in loop sinking position.

2. A flat knitting machine comprising a series 70 of sliding needles, knitting cams adapted to traverse in either direction along said needle series, a series of sinkers, two similar sinker cams adapted to traverse in either direction along said needle

series, and means to slide said cams alternately from loop sinking position to holding-down position and vice versa at the end of each traverse, in accordance with the alternate movements of the knitting cams in opposite directions, so as to 5 maintain the leading sinker cam in loop sinking position.

3. A flat knitting machine comprising a series 10 of sliding needles, knitting cams adapted to traverse in either direction along said needle series, a series of sinkers, sinker cams adapted to traverse in either direction along said needle series and to actuate said sinkers in a loop sinking operation positively in lead of said knitting cams, and a plate adapted to carry said sinker cams, 15 and to slide relatively to the needles at the beginning of each traverse in the direction of such traverse, so as to reverse the lead of said sinker cams at each reversal of traverse of the knitting cams.

4. A flat knitting machine comprising a series 20 of sliding needles, knitting cams adapted to traverse in either direction along said needle series, a series of sinkers, two similar sinker cams adapted to traverse in either direction along said needle series, a plate adapted to carry said sinker cams, and to slide relatively to the needles at the beginning of each traverse in the direction of such traverse, and a pin and slot connection adapted to resolve such sliding motion into a motion of 30 the sinkers into and out of loop sinking position, in accordance with the alternate movements of the knitting cams in opposite directions, so as to maintain the leading sinker cam in loop sinking position.

5. A flat knitting machine comprising a series 35 of sliding needles, knitting cams adapted to traverse in either direction along said needle series, a series of sinkers, sinker cams adapted to traverse in either direction along said needle series 40 in positive lead of said knitting cams, and a plate adapted to carry said sinker cams in their traverse, and to slide with the sinker cams at the beginning of each traverse in the direction of such traverse, so as to reverse the lead of said 45 sinker cams at each reversal of traverse of the knitting cams.

6. A flat knitting machine comprising a series 50 of sliding needles, knitting cams adapted to traverse in either direction along said needle series, a series of sinkers, two similar sinker cams adapted to traverse in either direction along said needle series in positive lead of said knitting cams, a plate adapted to carry said sinker cams and to slide with said sinker cams at the beginning of 55 each traverse in the direction of such traverse, and a pin and oblique slot connection between said sinker cams and said knitting cams, adapted to cause said sinker cams in their sliding movement to slide also in and out of loop sinking position respectively so as to maintain the leading sinker cam in loop sinking position.

7. A flat knitting machine comprising a series 65 of sliding needles, knitting cams, a series of sinkers, two similar sinker cams, a plate carrying said 65 sinker cams, means for traversing said knitting and sinker cams in either direction along the needle series, means for reversing the direction of traverse at the end of each traverse, means in connection with said reversing means to cause 70 said plate to slide relatively to the knitting cams in the direction of the next traverse, and a pin-and-slot connection between said sinker cams and said knitting cams adapted to cause the sinkers to move respectively into and out of loop 75

- sinking position upon the sliding motion of said plates, so as to maintain the leading sinker cam in loop sinking position.
8. A flat knitting machine comprising a series of bearded sliding needles, knitting cams adapted to be traversed in either direction along said needle series, a series of sinkers, sinker cams, pressers in connection with said needles, presser cams, said sinker and presser cams being adapted to traverse in either direction along said needle series and to operate upon the sinkers and pressers in positive lead of said knitting cams, and means for moving said sinker and presser cams relatively to said knitting cams so as to change the lead thereof over said knitting cams at each reversal of the traverse of the knitting cams.
9. A flat knitting machine comprising a series of bearded sliding needles, knitting cams adapted to be traversed in either direction along said needle series, a series of sinkers, sinker cams, pressers in connection with said needles, presser cams, said sinker and presser cams being adapted to traverse in either direction along said needle series and to operate upon the sinkers and pressers in positive lead of said knitting cams, a plate adapted to carry said presser cams, means for sliding said plate at the beginning of each traverse in the direction of such traverse so as to reverse the lead of said sinker cams at each reversal of the traverse of the knitting cams, and a cam carried by said plate adapted to effect the reversal of lead of the presser cams at each reversal of traverse.
10. A flat knitting machine comprising a series of bearded sliding needles, knitting cams adapted to be traversed in either direction along said needle series, a series of sinkers, sinker cams, pressers in connection with said needles, a pair of similar presser cams pivotally mounted in connection with said knitting cams, said sinker and presser cams being adapted to traverse in either direction along said needle series and to operate said sinkers and pressers in positive lead of said knitting cams, a plate adapted to carry said presser cams, means for sliding said plate at the beginning of each traverse in the direction of such traverse so as to reverse the lead of said sinker cams at each reversal of the traverse of the knitting cams, and a cam carried by said plate adapted to operate on said presser cams so as to swing the leading cam into and the following cam out of operating position thereby reversing the lead of the presser cams at each reversal of traverse.
11. A flat knitting machine comprising a series of sliding needles, knitting cams adapted to traverse in either direction along said needle series, a series of sinkers, sinker cams, a yarn guide for feeding yarn to the needles, said sinker cams and yarn guide being adapted to traverse along the needle series in either direction and to operate on the sinkers and on the needles positively in lead of said knitting cams, and means for moving said sinker cams and said yarn guide relatively to said knitting cams so as to change the lead thereof over said knitting cams at each reversal of the traverse of the knitting cams.
12. A flat knitting machine comprising a series of sliding bearded needles, knitting cams adapted to be traversed in either direction along said needle series, sinkers, sinker cams, pressers in
- connection with said needles, presser cams, a yarn guide adapted to feed yarn to the needles, said sinker cams, presser cams and yarn guide being adapted to traverse in either direction along said needle series and to operate upon said sinkers, pressers, and needles respectively in positive lead of said knitting cams, and means for moving said sinker cams, presser cams and yarn guide relatively to said knitting cams so as to change the lead thereof over said knitting cams at each reversal of the traverse of the knitting cams.
13. A flat knitting machine comprising a series of sliding needles, knitting cams adapted to traverse in either direction along said needle series, a series of sinkers, sinker cams adapted to traverse in either direction along said needle series and to actuate said sinkers in a loop sinking operation positively in lead of said knitting cams, and means adapted, at each reversal of traverse of the knitting cams, to move said sinker cams relatively to said knitting cams in the direction of the next traverse, so as to reverse the lead of the sinker cams preparatory to the next traverse.
14. A flat knitting machine comprising a series of sliding needles, knitting cams, a series of sinkers, sinker cams, common means adapted to traverse said knitting and sinker cams in either direction along said needle series, said sinker cams being adapted to actuate said sinkers in a loop sinking operation positively in lead of said knitting cams, and means adapted at each reversal of traverse of the knitting cams to move said sinker cams relatively to said knitting cams in the direction of the next traverse so as to reverse the lead of the sinker cams preparatory to the next traverse.
15. A flat knitting machine comprising a series of sliding needles, knitting cams, a series of sinkers, sinker cams, common means adapted to traverse said knitting and sinker cams in either direction along said needle series, said sinker cams being adapted to actuate said sinkers in a loop sinking operation positively in lead of said knitting cams, means in connection with said traversing means for changing the direction of traverse at the end of each traverse, and means operated by said changing means for moving said sinker cams relatively to said knitting cams in the direction of the next traverse so as to reverse the lead of the sinker cams preparatory to the next traverse.
16. A flat knitting machine comprising a series of sliding needles, knitting cams adapted to traverse in either direction along said needle series, a series of sinkers, sinker cams, a yarn guide for feeding yarn to the needles, said sinker cams and yarn guide being adapted to traverse along the needle series in either direction and to operate on the sinkers and on the needles positively in lead of said knitting cams, and means adapted at each reversal of traverse of the knitting cams to move said sinker cams and said yarn guide relatively to said knitting cams in the direction of the next traverse so as to reverse the lead of the sinker cams and the yarn guide preparatory to the next traverse.
